UNITED STATES PATENT OFFICE.

SAMUEL HAMLIN PIERCE, OF DESERONTO, ONTARIO, CANADA.

PLASTIC-CARTRIDGE-MAKING MACHINE.

1,092,451.

Specification of Letters Patent.

Patented Apr. 7, 1914.

Application filed July 30, 1912. Serial No. 712,227.

To all whom it may concern:

Be it known that I, SAMUEL HAMLIN PIERCE, of the town of Deseronto, in the county of Hastings, in the Province of Ontario, Canada, have invented certain new and useful Improvements in Plastic-Cartridge-Making Machines, of which the following is the specification.

My invention relates to improvements in plastic cartridge making machines and the object of the invention is to devise a simple machine for making cartridges from a plastic explosive compound, in which all the parts in excessive frictional contact with the explosive compound are effectually kept cool, and by which the plastic explosive compound is formed into cylindrical sections and suitably wrapped, and it consists essentially of a receiving hopper, a water jacketed cylindrical compression chamber having a contracted exit nozzle at one end, a feed screw located in the hopper, a compressing screw located in the compression chamber, suitable driving means for the compressing and feed screws, water cooling channels passing through the compressing screw, a receiving table, means for severing the compressed explosive compound into cylindrical sections as it is fed on to the table, means for imparting a step by step lateral movement operated at predetermined intervals to the feed table, and means operated by gravity for wrapping each cartridge section in a suitable covering as it is delivered from the receiving table as hereinafter more particularly explained by the following specification.

Figure 1, is a general perspective view of my device. Fig. 2, is a sectional plan view of my device. Fig. 3, is a vertical longitudinal section through the center of Fig. 2. Fig. 4, is a cross section on line $x-y$ Fig. 2. Fig. 5, is an enlarged sectional detail of the compression chamber and compressing screw.

In the drawings like letters of reference indicate corresponding parts in each figure.

A is the base of the machine.

A' and A² are the main standards to which are secured the supplemental standards A³ and A⁴. The standard A³ is provided with a top cross bar A⁵ and a cross bar A⁶ intermediately of its height. The standard A⁴ is provided with a top cross bar A⁷.

B is the cylindrical compression chamber provided with a water jacket B' provided

with a water feed pipe B², the water passing out therefrom through the pipe B³. The compression chamber B is supported on a suitable standard B⁴ and is provided with a receiving orifice B⁵ provided with a surrounding annular internal threaded flange B⁶.

B⁷ is a receiving hopper provided with an exteriorly threaded lower end B⁸ threaded into the internal thread of the flange B⁶ to shoulder against the top of the compression chamber so that its interior periphery is flush with the interior periphery of the compression chamber feed opening.

B⁹ is an exit nozzle provided with an internal threaded portion B¹⁰ (see Fig. 5) threaded on to the external thread of the annular flange B¹¹ extending around the exit opening of the compression chamber.

A⁸ and A⁹ are bearing brackets extending from the supplemental standard A³ and provided with vertical end bearings A¹⁰ and A¹¹.

C is a vertical shaft journaled in the bearings A¹⁰ and A¹¹ and provided at its upper end with a securing collar C' bearing upon the top of the bearing A¹⁰.

C² is a feed screw suitably secured to the lower end of the shaft C. The feed screw C² extends downwardly through the hopper B⁷ into the receiving orifice B⁵ of the compression chamber.

C³ is a horizontal shaft journaled in bearing brackets C⁴ and C⁵ secured respectively on the cross bars A⁶ and A⁷ of the standards A³ and A⁴. C⁶ is a bevel gear mounted upon the inner end of the shaft C³.

C⁷ is a bevel gear mounted on the vertical shaft C and meshing with the bevel gear C⁶.

E is a compressing screw shaft journaled in brackets E' and E² secured respectively to the standards A' and A². The shaft E is provided with channels E³ and E⁴ extending longitudinally through the shaft for a purpose which will hereinafter appear. The inner end of the shaft is provided with an annular flange E⁵.

E⁶ is the compressing screw provided with a hollow point E¹⁵ having a reduced external threaded portion E¹⁶ (see Fig. 5) threaded in to the internal threaded end E⁷ of the compressing screw body against the gasket E¹⁸. The compressing screw body is also provided with longitudinal channels E⁸ and E⁹ in alignment with the channels E³ and E⁴ of the compressing screw shaft thereby

forming continuations of the compressing screw channels leading into the hollow point E¹⁵.

F is the main driving shaft supported in bearings F' and F² secured to the standards A' and A².

F³ and F⁴ are pulleys mounted on the driving shaft F and F⁶ is a peripheral cam drum also mounted on the driving shaft F.

F⁷ is a pulley secured to the compressing screw shaft E.

F⁸ is a pulley mounted upon the compressing screw shaft E and forming also an internal frictional clutch drum.

F⁹ is a co-acting frictional clutch member slidably mounted upon the shaft E. The clutch member F⁹ is provided with any suitable form of engaging clutch lever F¹⁰ (see Fig. 3) whereby the clutch members F⁹ and F⁸ are connected together when drawn into engagement.

F¹¹ is an annular groove formed in the clutch member F⁹.

F¹² is an operating slidable clutch bar supported in bearings F¹³ and F¹⁴ formed respectively in the main standards A² and A'. The slidable bar F¹² is provided with a frictional roller F¹⁵ extending into the groove F¹¹. The cam drum F⁶ is provided with a cam way F¹⁶ having an offset F¹⁷.

F¹⁸ is a roller journaled on the slidable bar F¹². The roller F¹⁸ extends into the cam way F¹⁶.

H is a receiving water chamber preferably annular in form and provided with an inlet pipe H' and an exit pipe H² extending through the stuffing box H³. The pipe H² extends axially through the stuffing box H³ and is provided with a curved end H⁴ extending into the passageway E⁴ (see Fig. 2).

H⁵ is a stuffing box by which a water tight joint is formed between the compressing screw shaft E and the water chamber H.

I is a pinion mounted on the compressing screw shaft E² and I', is a gear mounted on the driving shaft F.

J is a tubular shaft journaled at one end in the bearing J' forming part of the standard A and at the opposite end in the standard J².

J³ is a shaft journaled at one end in a bearing formed beneath the standard A². The opposite end of the shaft extends through the hollow shaft J and is journaled at its extreme end in the bearing standard J².

K is a counter shaft mounted in bearing standards K' and K².

K³ is a drum mounted upon the shaft J. K⁴ is a similar drum mounted upon the shaft K.

K⁵ is a belt of leather or any other suitable flexible material mounted upon the drums K³ and K⁴.

K⁶ are a series of cross slats forming a receiving table. The slats are secured to the belt K⁵ and provided with opposing inclined faces K⁷ and K⁸ onto which the cartridge 2 is fed.

L is an idler pinion mounted upon the stud shaft L' journaled in the bearing standard L².

L³ is a gear mounted on the shaft K and meshing with the pinion L.

L⁴ is a gear similar to L³ mounted upon the shaft J³ and meshing with the pinion L diametrically opposite the gear L³.

M is a notched wheel mounted on the shaft K. The number of notches in the wheel M correspond to the number of intervening spaces between the cross slats K⁶.

M' is an arm swung upon the shaft J³ and provided with a forked end M² between which is journaled the roller M³ bearing upon the top of the notched wheel M.

M⁵ are tension springs connecting the forked end of the arm M' with the collar M⁶ loosely mounted upon the shaft K.

N is a shaft journaled in suitable bearings and provided with a gear N³ meshing with the gear N⁴ mounted upon the shaft J³.

N⁵ is a lantern wheel mounted upon the shaft J³ and N⁶ is a finger mounted upon the shaft N.

O is a pulley mounted upon the shaft C³.

O⁴ is a belt connecting the pulley O with the pulley F⁷ mounted upon the compressing screw shaft E. Curved knives P are mounted on the shaft J on both sides of the drum K³.

Q is a receiving table having an inclined portion Q' upon which the cylindrical sections of the cartridge roll 2 are delivered from the table formed by the slats K⁶.

Q² is a gear mounted on the shaft N and meshing with the pinion I.

Having described the principal parts involved in my invention I will briefly describe the operation of the same. The explosive compound is fed in a loose state into the hopper B⁷ from which it is fed by the feed screw C² through the opening B⁵ into the compression chamber B.

The compressing screw shaft and feed shaft are revolved, the pressure screw E⁶ is thrown into gear by the cam F⁶ operating the clutch F⁸, F⁹, forcing the material in the direction of the arrow through the nozzle B⁹ compressing it into a cylindrical form and depositing it between the pair of slats K⁶ between the inclined faces K⁷ and K⁸ thereof as indicated in Fig. 4 of the drawings.

The compressing screw and feed screw, it will be readily understood, is driven from the shaft F through the pulley F³, belt F¹⁹, clutch pulley F⁸, clutch member F⁹ which are normally in engagement and mounted on the shaft E thereby driving the shaft E. The feed screw is driven from the shaft E by the pulley F⁷,

125

driving the shaft E through the pulley F³, belt F¹⁹, clutch pulley F⁸, clutch member F⁹ which are normally in engagement and mounted on the shaft E thereby driving the shaft E. The feed screw is driven from the shaft E by the pulley F⁷,

130

belt O⁴, pulley O, shaft C³, gears C⁶ and C⁷ mounted on the shaft C to which the feed screw is connected. The clutch members F⁸ and F⁹ are then drawn out of engagement by 5 the offset F¹⁷ in the cam way F⁸ operating the clutch rod F¹², engaging cam way F¹⁶ and the annular groove F¹¹ of the clutch member F⁹. The shaft N is driven from the shaft F through the gear wheels I' and Q² 10 and idler pinion I. The table combining the slats K⁶ and belt K⁵ is intermittently driven from the shaft N by the finger N⁶. Immediately the clutch members F⁸ F⁹ are thrown out of gear slipping the compressing and 15 feed screws the finger N⁶ is revolved by the shaft N engaging the lantern wheel N⁵ rotating the lantern wheel a definite space, turning the shaft J³, gear L⁴, idler pinion L and gear L³ to turn the shaft K and drum 20 K⁴ mounted thereon and thereby driving the belt K⁵ so as to carry the slats K⁶ a predetermined distance. The knives P are rotated by means of the hollow shaft J driven by the gears N⁴ and N³ from the shaft N. It will 25 thus be seen that the compressing screw shaft is first stopped by the cam F⁶ operating the clutch F¹¹, F⁸ after the cylindrical cartridge is fed on to the receiving table formed by the slats K⁶. The knives P are so timed as to 30 then cut the cylindrical mass into sections of a definite length. The table operated by the finger N⁶ is then carried in the direction of arrow carrying the cartridge away from opposite the point of delivery of the nozzle B⁹. 35 The feed and compressing screw is then again thrown into gear and another cartridge is delivered on to the slats K⁶. The operation is continued, the cartridge being successively delivered on to the inclined portion Q' of the table Q down which they roll. Wrapping paper is previously placed on the 40 table Q over which the cartridge passes, the paper adhering to the cartridge as it rolls over the same and forming a wrapping or covering. This movement of the table comprising the slats K⁶ is controlled by the roller M⁸ dropping into a notch formed in the wheel M thereby bringing the table to a 45 definite position and centering the space between the slats K⁶ exactly opposite the center of the nozzle B⁹. It will also be seen that the body of the compressing screw is kept cool by water pressure passing from the chamber H through the channel E³ and 50 channel E⁸ into the hollow point of the screw E¹⁵, the water returning through the passageway E⁹ and passageway E⁴ into the waste pipe H² leading to a suitable ice tank from which it may be returned to the water 55 chamber.

In this description I have disclosed a very

simple form of machine in which the compressing and feed screws re-operated intermittently and alternately with an intermittently movable receiving table, allowing for 65 the severing of the cartridge lengths and removal to the wrapping table.

What I claim as my invention is.

1. In a plastic cartridge making machine, 70 the combination with the cylindrical compression chamber having a discharge nozzle and receiving hopper, and means for compressing the mass fed into the compression chamber, and forcing it through the delivery nozzle in cylindrical form, of a receiver comprising a pair of shafts, a drum mounted on each shaft, a belt mounted on the drum, cross slats secured to the belt, gears connecting the shafts together, a pin gear on one of the shafts, and a suitable driving shaft carrying a finger co-acting with the pin gear mounted on the aforesaid shaft, to turn the receiver a definite space on each revolution of the driving shaft, and means for severing the cartridge section from the cylindrical mass as it 85 is delivered on to the cross slats of the receiver, as and for the purpose specified.

2. In a plastic cartridge making machine, 90 the combination with means for compressing the plastic material into cylindrical form, of an endless receiving table provided with an endless series of cross slats suitably spaced apart, means for connecting the slats together, supporting shafts and drums for the slats, a notched wheel mounted on one of the supporting shafts, means for centering the slat intervening space opposite the center of discharge comprising an arm swung upon a suitable bearing, a roller journaled on the arm and spring tension means for holding the roller in contact with the notched wheel, 95 as and for the purpose specified.

3. In a plastic cartridge making machine, 105 the combination with the cylindrical compression chamber having a discharge nozzle and receiving opening, of a main shaft, a peripheral cam mounted thereon, a compressing screw shaft, a compressing screw mounted thereon and operating in the compression chamber, a clutch and clutch pulley mounted on the compressing shaft, a pulley 110 mounted on the driving shaft, a belt connecting the pulley on the driving shaft with the clutch pulley on the compressing shaft, and means for operating the clutch from the peripheral cam, as and for the purpose specified.
